DESIGN FOR A RACK FOR MICROSCOPIC SLIDES OR SIMILAR ARTICLE

Vivian Ray Bennett, Yucca Valley, near
Whitewater, Calif.

Application June 16, 1947, Serial No. 139,715

Term of patent 7 years

(Cl. D57—1)

To all whom it may concern:

Be it known that I, Vivian Ray Bennett, a citizen of the United States, residing at Yucca Valley, near Whitewater, in the county of San Bernardino and State of California, have invented a new, original, and ornamental Design for Rack for Microscopic Slides or Similar Article, of which the following is a specification, reference being had to the accompanying drawing, forming a part thereof.

Figure 1 is a top perspective view of a rack for microscopic slides, showing my new design, the broken outline of a slide being for illustrative purposes only.

Figure 2 is a top plan view thereof.

Figure 3 is a view in end elevation.

I claim:

The ornamental design for a rack for microscopic slides or similar article, substantially as shown and described.

VIVIAN RAY BENNETT.
